REACTION RESISTING DEVICE FOR USE WITH POWER EXCAVATORS

Filed Oct. 17, 1925

UNITED STATES PATENT OFFICE.

GUY E. SCOTT, OF PAINESVILLE, OHIO, ASSIGNOR OF ONE-HALF TO ELMER FRESHWATER, OF PAINESVILLE, OHIO.

REACTION-RESISTING DEVICE FOR USE WITH POWER EXCAVATORS.

Application filed October 17, 1925. Serial No. 62,985.

My invention relates to reaction-resisting devices for use with power excavators. Particularly, the invention relates to a new and improved blocking device to withstand the 5 thrust of the excavator when the scoop or trencher is pushed or pulled into the material which is being removed by the mechanism.

The annexed drawing and the following 10 description set forth in detail certain means embodying my invention, such means constituting, however, but two of the various forms in which the principle of the invention may be applied.

15 In said annexed drawing:

Figure 1 represents a side elevation of a power excavator to the rear of which is attached one form of my reaction-resistance device, one of said devices being also shown 20 in dot-and-dash lines attached to the front of the mechanism;

Figure 2 is an elevation, upon an enlarged scale, of the reaction resistance device, shown 25 in Figure 1, taken from the plane indicated by the line II—II, Figure 1;

Figure 3 is a side elevation of this device;

Figure 4 is a fragmentary vertical longitudinal section of a power excavator, showing some parts in side elevation, to which is 30 attached a modified form of my reaction-resistance device, one of the applications of the same being shown in dot-and-dash lines, with a small portion of a certain I-beam broken away, the scale being substantially 35 twice as large as that used in Figure 1; and

Figure 5 is an elevation of the device shown in Figure 4, taken from the plane indicated by the line V—V, Figure 4.

Referring particularly to the annexed 40 drawing in the several views of which the different elements are respectively designated by the same ordinals, I suggest the frame of a power excavator by the ordinal 1, to the front end of which is pivotally supported a 45 swinging boom 2 from which depends a scoop 3 adapted to be moved upon a trolley longitudinally of the boom 2 by means of power devices well known in this art. I have illustrated a skimmer scoop 3 which in ordinary 50 practice is moved forwardly to obtain a load. This forcing of the scoop 3 forwardly produces a reactive thrust upon the frame 1 tending to cause the same to move rearwardly. I have designed my reaction-re-

sistance device to prevent this rearward movement of the excavator. To this end I have shown one form of my device attached to the rear of the excavator in Figure 1. However, the device will function as efficiently for use with those types of excavators 60 in which the scoop or trencher is pulled rearwardly and in which, hence, the tendency of the reaction is to move the excavator frame forwardly. The same reaction-resisting device may be attached and used either at the 65 front or the rear of the mechanism and I have indicated the use of the same at the rear in Figure 1 by the full line drawing and the possible use at the front by the dot-and-dash drawing.

Referring particularly to Figures 1, 2 and 3, I rigidly secure forwardly and rearwardly of the frame 1 plates or brackets 4 to which are secured one end of inclined bars 5, the bars 5 at the rear inclining toward the 70 rear and the bars 5 at the front inclining toward the front. The members 4 and 5 are rigidly secured to the frame 1 and intended to be stationary. I removably secure to the bars 5 my blocking member proper. In the 75 form shown, this blocking member comprises a longitudinal I-beam 7 to the adjacent flanges upon one edge of which are secured a pair of spaced opposed open frames 80 comprised of angles 8 strengthened by means of 85 gusset plates 9 secured to and intermediate of the two angle frames at the corner portions thereof. I provide a further brace in the form of a transverse angle 10 secured by other gusset plates 10' to the pair of angle 90 frames intermediate the corners thereof. In order that the blocking member may positively engage the soil or other foundation 95 over which the excavator is acting, I secure to the bottom edge of the angle frames a 100 soil-engaging foot 11 and, in the form of device illustrated in the accompanying drawing, this foot 11 takes the form of a Z-shaped bar. I detachably secure the blocking member just described to either the front bars 5 or the rear bars 5, according to the type of 105 excavator mechanism which is being used. It is well known that the excavator mechanism is constantly moving its position during the recurrent loading and dumping of the scoop 3 so that in order to provide for the drag of the blocking member over the soil 12 when the excavator moves forwardly,

in the type of mechanism shown in Figure 1, I pivotally secure the blocking member to the bars 5 by means of pins 6.

In order to provide for lifting the blocking member out of contact with the ground 12, when it is desired to put the same out of commission and yet not remove it from the support 5, I attach to the lower end of the blocking member a cable or series of cables 13 which pass up over pulleys 14 secured to the excavator frame 1. Suspended from the free ends of the cables 13 are counterweights 15 which upon being manually depressed to lift the lower end of the blocking member 15 will retain the latter in the desired upper and inactive position, plainly shown by dot-and-dash lines at the right-hand end of Figure 1.

In Figures 4 and 5 is shown a modified type of my blocking device. The modification consists in different means for supporting the blocking member proper upon the excavator frame. As shown, a transverse shaft 16, preferably one of the axle 25 shafts, is provided with a pair of split collars comprising members 17 and 18 detachably bolted together, the collars as a whole being rotatable upon the shaft 16. One part of the collar, for instance, the member 18 is formed with a boss 19 providing convenient means to which to bolt the I-beam 7 of the blocking member proper. Referring particularly to Figure 4, the arrangement is shown in full lines which will prevent the 35 forward thrust of the excavator frame. The same set of collars serves for both operations. When it is desired to change from the front to the rear, for instance, of the rear axle 16, the collar parts 18 are separated 40 from the collar parts 17 and the blocking member proper and the collars reassembled in the position suggested by dot-and-dash lines, Figure 4. It would be possible to detach the I-beam 7 from the bosses 19 but it 45 is believed that it is preferable to separate

the two parts of the split collars. It is evident that by reason of the rotation of the split collars upon the shaft 16 the drag of the blocking member over the soil 12, when the excavator mechanism shifts its position, is provided for, and yet the direction of thrust is such that this loose mounting of the split collars upon the shaft 16 does not prevent the blocking member from resisting the forward thrusts in the position shown in 55 full lines and the rearward thrusts of the machine in the position shown in dot-and-dash lines, when the scoop or trencher is forced into the soil.

The construction described provides very 60 economical and convenient mechanism for the desired purpose; mechanism which can be utilized either for the forward or rearward thrust of the machine; and which can be readily removed when the service of the 65 same is not desired, or readily removed and replaced when it is desired to shift the device from service against front thrust to service against rear thrust or vice versa.

What I claim is:

A blocking member for reaction-resisting devices utilized with power excavators comprising an I-beam; a pair of opposed spaced frames rigidly secured along one edge to said I-beam, each of said frames comprising peripheral angle members; strengthening members secured to and intermediate of said angle frames at the corner portions thereof; other strengthening members secured to said angle frames intermediate the 70 corners thereof; and a soil-engaging foot secured to the opposite edge of said angle frames, said soil engaging foot being Z-shaped in cross-section and having the web of the Z secured flatwise to the said opposite edge and at right angles to the general plane of the frame members.

Signed by me this 22nd day of Sept., 1925.

GUY B. SCOTT.
